ATTORNEY

UNITED STATES PATENT OFFICE.

JAMES A. McGEE, OF NEW YORK, N. Y.

DESIGN FOR A SHRINE.

SPECIFICATION forming part of Design No. 18,181, dated March 13, 1888.

Application filed January 10, 1888. Serial No. 260,360. Term of patent 7 years.

To all whom it may concern:

Be it known that I, JAMES ALEXANDER McGEE, of the city, county, and State of New York, have invented and produced a new and original Design for a Shrine, of which the following is a specification, reference being had to the accompanying photograph, forming part thereof, which gives a front view of my newly-designed shrine.

10 The leading feature of my design consists of a figure of the Virgin represented as standing in an attitude of supplication in the recess of an ornamental panel, with child angels in attitudes of devotion and clusters of flowers on either side.

15 A designates a panel, which is surmounted by a cross, B, and the framing of which is ornamented with parallel lines of beads, L, and therebetween with relief representations of straight twigs, C, arranged to form a Grecian border, and leaves D, shooting out from the

twigs into the alternate reverse spaces formed by the border. In the heart of the panel is a recess, E, the top and sides of which are decorated with drapery F, and the back G of which is ornamented with scrolls and other figures of fanciful design. On a pedestal, H, on the floor of the recess E a draped figure, I, of the Virgin is represented as standing in an attitude of supplication. Statuettes J, representing child angels seated in attitudes of devotion, are arranged on the floor of the recess at either side of the figure of the Virgin, and clusters K of flowers are back of the statuettes J and tower above the same. 35

I claim—

The design for a shrine, substantially as herein shown and described.

JAMES A. McGEE.
